CLAIM

The ornamental design for a collapsible truck cap, as shown and described.

DESCRIPTION

FIG. 1 is a perspective view of the collapsible truck cap embodying the design of the present invention;

FIG. 2 is an enlarged front elevational view thereof;

FIG. 3 is an enlarged rear elevational view thereof;
FIG. 4 is an enlarged side elevational view thereof, the side opposite being a mirror image of the side shown in FIG. 4;

FIG. 5 is a top plan view thereof; and.

FIG. 6 is a bottom view thereof.

FIG. 1

FIG. 4

FIG. 2

FIG. 3

FIG. 6

FIG. 5
